UNITED STATES PATENT OFFICE.

ALEXANDER D. CLARKE, OF OMAHA, NEBRASKA.

AMALGAMATING APPARATUS.

SPECIFICATION forming part of Letters Patent No. 253,843, dated February 21, 1882.

Application filed November 22, 1881. (No model.)

To all whom it may concern:

Be it known that I, ALEXANDER D. CLARKE, of Omaha, Douglas county, State of Nebraska, have invented certain new and useful Improvements in Amalgamating Apparatus, of which the following is a specification.

This invention relates to devices for governing the feed of sand to the blast in that class of amalgamators wherein a blast is employed for carrying the sand to the amalgamating parts of the apparatus.

The accompanying drawings show at Figure 1 a partial side elevation of an amalgamator to which the present invention has been applied. Fig. 2 is a cross-section. Fig. 3 is an enlarged detail view of the wind-gate and hopper-valve actuating devices. Fig. 4 is an enlarged sectional detail, showing the wind-gate; and Fig. 5 is a vertical section of the feed-hopper and its valve.

Similar letters of reference indicate like parts wherever the same are used.

In said drawings, A represents the air-chest, which is charged with air by the blower.

B is the screening apparatus, having a delivery-spout, b; and C C, the main blast-conducting pipes, which lead into the upright hollow standard C', upon which latter the amalgamating-boxes shown in my former patents of September 27, 1881, or equivalent devices for the same purpose, are supported.

D is a hollow upright supporting the feed-hopper D' and receiving a minor portion of the blast through the conducting-tube D², the material received by the hopper being carried by the blast through a goose-neck connection (such as is shown in my said patents) to the amalgamating-boxes upon the upright C'. I have not thought it necessary to show this goose-neck or the amalgamating-boxes, as they are fully set forth in said patents.

The main blast-conducting pipes C C, I connect by a cross-pipe, E, at a point between the upright D and the standard C', and centrally in the top of this cross-pipe E is inserted a vertical cylinder, E', which contains a spring-depressed piston, E². This piston is steadied at its upper end by a bearing, e, standing out from the part D, and is connected by one or both of the braces e' and their right-angled extensions e² to vertical rods E³, located one at each side

of the part D, and through such rods and said cross-pieces and extensions it operates the wind-gate, as presently to be explained, and also the hopper-valve d, which is secured to the extensions e² of the upper cross-brace, e', and by this latter connection gages the amount of sand fed to the portion of the blast passing through the conductor D² and goose-neck D. The lower ends of the rods E³ are provided with wrist-pins f, which are inserted in slots f' in the angle-pieces F, pivoted to standards F', and connected by rods F² to the toggles F³, by which toggles, through the medium of slotted rods F⁴ and the top cross-brace, g, of the wind-gate G, which is inserted in the conduit D², said gate is opened and closed. By thus actuating the wind-gate the blast is regulated by the power which is derived from the piston E². As will be noticed, the angle-pieces have several openings, by which the rods F² may be attached thereto, and that the toggle-pieces are also provided with openings, which permit the length of its members to be changed to suit circumstances.

The nuts f⁴ upon the rods permit a variety of adjustment, and if it is desired that the gate shall not respond immediately to the movement of the piston the lower nuts may be turned down, which will allow the rods to rise to some extent before they begin lifting the gate.

In order that the hopper-valve may work easily, I balance it by counterpoises, which are weighted levers H, fulcrumed at h, and connected to the rods E³.

The operation of the invention is as follows: Air, being admitted to the air-chest from the blower, immediately fills the pipes C C and causes a pressure upon the piston, raising the latter according to the amount of air-pressure. The piston raises the rods E³, which tip the angle-pieces F upon their pivots f⁵ and actuate the rod F² to lengthen the toggle F³, and thus to elevate the rods F⁴, and sooner or later, according to the adjustment given the nuts f⁴, to elevate the gate also. At the same time the hopper-valve is also raised through the rods E³ and the braces connecting them with said valve.

It will be understood, of course, that the nuts e³ upon the piston and upon said rods E³ may also be adjusted so that the hopper-valve

will immediately feel the rise of the piston, or so it will not do so until after the piston has risen some distance, this adjustment being permitted in the same way as that of the wind-gate.

5 With this construction it is easy to adjust the blast to the feed and the feed to the blast, and when thus adjusted to maintain the proper relation between the two. This is very desirable, because the varying conditions of the material, which may be wet, dry, fine, or coarse, require different treatment.

10 Pinions with bushings may be placed upon the wrists *f* to obviate friction.

15 The springs, by which the piston is depressed, insures the return to the normal position as soon as the blast-pressure ceases.

I claim—

1. In combination with blast-conducting de-

20 vices to which and the hopper by which the sand is fed, a wind-gate in the former and a valve in the latter, and devices for actuating the said gate and valve simultaneously or substantially simultaneously, substantially as specified.

25

2. The combination, with the hopper-valve, of governing mechanism and conduits for conducting the actuating-blast to said mechanism, substantially as specified.

3. The combination, with the wind-gate, of 30 governing mechanism, conduits for conducting the blast to said mechanism, and the devices for conveying motion from the said mechanism to the gate, substantially as specified.

ALEXANDER D. CLARKE.
